UNITED STATES PATENT OFFICE.

JAMES K. P. PINE, OF LANSINGBURG, NEW YORK.

DESIGN FOR A COLLAR.

SPECIFICATION forming part of Design No. 18,925, dated February 12, 1889.

Application filed December 24, 1888. Serial No. 294,553. Term of patent 7 years.

To all whom it may concern:

Be it known that I, JAMES K. P. PINE, of the village of Lansingburg, county of Rensselaer, and State of New York, have invented 5 a new and useful Design for Apparel-Collars, of which the following is a specification.

My invention of a design is for the form of an apparel-collar, as shown in the accompanying drawings, forming a part of this specification, in which—

Figure 1 is a perspective and Fig. 2 a plan view of the collar.

My design consists of a collar-body having the straight bottom edge, B, continued throughout the length of the collar, the centrally-located straight and rear top edge part 15 of the collar, indicated at E, and which is parallel to the bottom edge, B, the ogee-curve part C, arranged in the top edge of the collar at each 20 side of the latter, said curves each being extended downwardly and frontwardly toward the ends, and the points P, arranged on the top edge of the collar at each side of the front, between each of said curves and the button-

hole tabs T, with said points P turned down- 25 wardly and outwardly on an angle.

Having thus described my design, what I claim, and desire to secure by Letters Patent, is—

The design for the form of an apparel-collar, 30 consisting of the collar-body having straight bottom edge, B, the straight upper top edge part, E, arranged to be parallel to the bottom edge part, B, the ogee curve C, arranged at each side in the top edge near the front ends, 35 and the point P, arranged at each side of the collar at the front ends, between the said curves and the button-hole tabs, and turned downwardly on an angle, as shown and described. 40

Signed at Troy, New York, this 14th day of December, 1888, and in the presence of the two witnesses whose names are hereto written.

JAMES K. PINE.

Witnesses:

CHARLES S. BRINTNALL,
W. E. HAGAN.
